Clifford E. Grube, Chicago, Ill., assignor to Belmont Radio Corporation, a corporation of Illinois

Application June 14, 1945, Serial No. 120,084

Term of patent 7 years

(Cl. D56—4)

To all whom it may concern:

Be it known that I, Clifford E. Grube, a citizen of the United States, residing at Chicago, in the county of Cook and State of Illinois, have invented a new, original, and ornamental Design for a Combination Radio-Phonograph Cabinet, of which the following is a specification, reference being had to the accompanying drawing, forming part thereof, in which:

Fig. 1 is a perspective view and Fig. 2 a top

view of a combination radio-phonograph cabinet embodying my new design.

The characteristic features of my new design are shown in solid lines in the drawing.

I claim:

The ornamental design for a combination radio-phonograph cabinet, substantially as shown and described.

CLIFFORD E. GRUBE.
